UNITED STATES PATENT OFFICE.

OSCAR FARRAR, OF CHICAGO, ILLINOIS.

IMPROVEMENT IN SEWING-MACHINES.

Specification forming part of Letters Patent No. 136,314, dated February 25, 1873.

To all whom it may concern:

Be it known that I, OSCAR FARRAR, of Chicago, in the county of Cook and State of Illinois, have invented certain Improvements in Sewing-Machines, of which the following is a specification:

My invention relates to that class of machines in which a rotating hook is employed to carry the needle-thread over a bobbin containing the under thread—such, for example, as the well-known Wheeler & Wilson machine; and the objects of the invention are to provide a loop-check for the upper thread which shall be yielding but positive in its operation; to prevent the gradual increase in the tension of the lower thread, which takes place in the present machines, as the thread is used from the bobbin; to furnish better means for regulating the tension of the under thread; and to accomplish other minor results, as hereinafter explained. The invention consists in the employment of a bobbin case or carrier of peculiar construction provided with a loop-check for the upper thread, with tension devices for the under thread, and so shaped as to facilitate the passage of the upper thread over it; and also consists in providing the rotating hook with an eccentric recess to receive the bobbin and case in order to move them edgewise.

Figure 1 is a face view of the rotating hook, with my bobbin-case and the bobbin in place therein; Fig. 2, an inside face view of the sliding-ring which holds the bobbin and bobbin-case in place in the recessed side of the hook, showing the shoulders or projections which limit the rotary or rocking movement of the bobbin-case; Fig. 3, a vertical central section through the rotating hook, with the bobbin-case and bobbin in place therein; Fig. 4, a vertical central section through the rotating hook, showing the square-edged recess to receive the bobbin-case; Fig. 5, a bottom-edge view of the bobbin-case; Fig. 6, a vertical central section through the bobbin-case turned upside down; Figs. 7 and 8, diagrams showing, respectively, the manner in which the bobbin-thread passes to the fabric and the eccentricity of the recess in the rotating hook; Fig. 9, a top-edge view of the bobbin; Fig. 10, a face view of the rotating hook, with the bobbin and its case in position; Fig. 11, an inside face view of the

bobbin-case, bobbin, and a portion of the rotating hook, illustrating the manner in which the upper thread presses the bobbin sidewise so as to cause friction thereon, and assist in producing the tension of the under thread; Fig. 12, a side view of the spring which is used in the bobbin-case to assist in giving the tension to the under thread; and Fig. 13, a top view of the hook, bobbin-case, and sliding-ring.

A represents the main shaft of the machine, which is provided on its end with the rotating hook B to hold the bobbin and carry the needle-thread around the same. The hook may be constructed in any suitable manner; but in the present instance I have represented the hook of the Wheeler & Wilson machine, having a recess or cavity in its outer side to receive the bobbin. C represents the bobbin, made in the usual lenticular form to fit within the recess in the side of the hook. D represents my bobbin-case, which consists of a light metal shell, made of a concave form so as to cover one side of the bobbin and encircle the outer edge of the same, and provided on its inside with a central stud or pivot, d, for the bobbin to turn upon. The recess in the side of the rotating hook B is made of such size that it will admit not only the bobbin but the edges of the bobbin-case also, as shown in Fig. 3, so that the hook carries the loop of the upper thread around both bobbin and bobbin-case. The bobbin-case is held in place in the hook by means of a ring-slide, E, which is fastened against the outer side of the case, as shown in Fig. 13, in the same manner that it is ordinarily used to hold the bobbin in place in the Wheeler & Wilson machine. The edges of the recess in the hook which receives the bobbin-case are made square, or at right angles to the face of the hook, as shown at t, Figs. 3 and 4, so that there is no tendency of the case to work out or to wedge fast when the bobbin-thread draws edgewise upon it. When the bobbin-case is applied the bobbin is enclosed between it and the hook, as shown in Fig. 3, so that it is allowed to rotate freely, but is held by the pivot d from moving edgewise and wedging fast, as it would otherwise do. The bobbin-case is not intended to rotate, except to a slight extent back and forth. In order to limit its movement two openings, g,

are made in its side so as to leave a bar, *h*, between them, as shown in Figs. 1 and 13, and then the ring-slide provided with two shoulders or projections, *f*, as shown in Fig. 2, which enter the openings on opposite sides of the bar, as shown in Fig. 13, so that the case can only rotate or rock back and forth until the bar *h* comes in contact with one or the other of the shoulders on the ring-slide. On the lower outer side of the bobbin-case, in rear of the center, I form a hook or horn, *r*, which serves to check the loop of the upper thread, and takes the place of the brush-check used in the Wheeler & Wilson machine. When the machine is in operation the loop of the upper thread, passing over the case *D*, is caught and held by the hook or check *r* until the continued rotation of the rotating hook casts it off therefrom. The shape of the check *r* and the arrangement of the rotating hook are such that the loop is cast off at the instant the rotating hook enters the next loop of the needle-thread. As the loop of the needle-thread tightens up and draws upon the check-hook *r* the bobbin-case turns forward and allows the check-hook to rise until the strain on the needle-thread is relieved. By thus arranging the check-hook so that it will yield under the strain of the upper thread I obviate all danger of unduly straining said thread. After the bobbin-case has been turned forward by the loop of the needle-thread drawing upon the check-hook *r* it is turned back again by the action of the under thread, which issues from the front side of the bobbin-case and passes backward and upward, as hereafter explained. The bobbin-case I provide in its lower edge with a hole, *i*, and in its upper edge with a number of holes, *j*, all but one of which latter are forward of the center. The bobbin-thread I pass out through the hole *i*, and then up through one of the top holes *j*, whence it passes to the fabric, as shown at *G*, Figs. 1 and 10. When the bobbin-case is turned forward by the strain of the upper thread on the check-hook, as before described, sufficient thread is unwound from the bobbin to form the next stitch. The manner in which this is done will be readily seen by reference to Fig. 7, in which *n* represents the point at which the thread issues before the bobbin-case is turned forward, and *o* the point at which it issues after the case is moved. A certain length of thread extends from the hole at *n* to the stitch being formed at the needle; but as the bobbin-case turns forward the hole recedes from the needle, so that an increased length of thread is required to extend from the hole to the needle, and the thread is consequently caused to unwind from the bobbin. The thread thus unwound and drawn out is, as before stated, sufficient to form the next stitch. The loop of the upper thread, after being cast off from the check-hook *r*, is drawn up by the needle so as to draw the bobbin-thread up into the fabric. When the needle-thread thus draws upon the bobbin-thread, which is just after the

bobbin-case is turned forward to unwind the thread, the bobbin-thread is tightened up so as to turn the bobbin-case back to the position in which it stood before it was turned forward by the action of the needle-thread against the check-hook. When the bobbin-thread is drawn up into the fabric no additional thread is drawn from the bobbin, but merely that which was unwound by the forward movement of the case taken up. The only resistance to the bobbin-thread being taken up is due to the resistance which the bobbin-case offers to being turned backward. This resistance, which is due to the friction of the case against the ring-slide, is uniform and unchangeable, and consequently the tension of the bobbin-thread remains always the same, excepting, of course, when it is purposely changed, as hereafter described. The uniform tension of the thread is, of course, due to the fact that the thread is not drawn directly from the bobbin into the fabric, but is first unwound by a separate, independent operation, and then its tension given by devices which offer a uniform resistance. In the ordinary machines the tension increases because the thread is drawn from the bobbin direct, and the bobbin offers increased resistance as the thread nears the center. The tension of the bobbin-thread depends upon the amount of resistance which the bobbin-case offers to being turned backward. This resistance is due entirely to the friction of the case against the ring-slide, caused by the loop of the upper thread drawing against the inside of the bobbin and case, so as to press the case outward against the slide-ring. It therefore follows that the greater the tension of the upper thread the greater the friction of the case against the slide and its resistance to being turned backward, and, consequently, the greater the tension of the bobbin-thread. This action of the upper thread upon the tension of the lower thread is very similar to that in the Wheeler & Wilson machine, and is what is known in the trade as the "automatic tension of the under thread." The tension of the under thread is also regulated by passing it through one or another of the holes *j* in the bobbin-case. When passed through one of the holes near the needle it draws nearly in line with the center of the bobbin-case, and at a great disadvantage, so that a strong tension is produced on the under thread in drawing it back; but, when passed through the holes at a greater distance from the needle, it has a greater leverage, and turns the case back with more ease, and therefore less tension is produced on the thread. By passing the thread through a hole very near the needle a tension may be produced sufficient to keep the under thread straight on the under side of the fabric, although a strong upper tension be also used. This arrangement will be found very valuable in working button-holes.

As a further means of causing a tension on the lower thread, I secure within the bobbin-case a flat spring, *k*, having in one end an eye

or hole through which the thread is passed, as shown in Fig. 6, so that the spring bears upon it. The end of the spring I provide with a lip, *n*, which projects out through the side of the bobbin-case, as shown in Figs. 1, 5, 6, and 10, so that when the loop of the upper thread engages on the check-hook *r* it bears on the lip and raises the spring so as to relieve the tension of the under thread for the moment. By thus relieving the tension I permit bobbin-case to turn easily under the action of the needle-thread loop, so as to obviate all danger of straining said thread. This spring is not, however, an essential feature, and it may be dispensed with; or it may be used without the lip *n* either in the bottom or top of the bobbin-case, as preferred.

In order to facilitate the passage of the needle-thread around the bobbin and bobbin-case, the recess in the rotating hook to receive the bobbin-case is made slightly eccentric to the centers of the hook and slide-ring, so that it moves the bobbin and case edgewise in a circle eccentric to the slide-ring. The movement is so timed that the bobbin-case is drawn back from the ring-slide just in advance of the upper thread-loop, as the latter passes around, so that an open space is left between the bobbin-case and slide-ring for the passage of the thread. The thread is thus allowed to pass through with far less strain than in the ordinary machines, in which the loop is required to force the bobbin and slide-ring apart. In order to further facilitate the passage of the loop, the inner edge of the bobbin-case is cut away or provided with a recess, *s*, as shown in Fig. 9, so as to permit the thread to pass without binding. As a still further means of facilitating the passage of the thread, I make the rear edge of the bobbin-case wider or thicker than the front, so as to throw the rear edge of the bobbin outward, and permit the thread to pass down in a straight line from the upper edge of the hook behind the bobbin and around the point of the hook. This is not, however, shown in the drawing, and is not considered essential, although beneficial.

Referring back again to the manner in which the lower thread, when drawn into the fabric, turns the bobbin-case back to its first position, it should be observed that about as each stitch

is being completed the tension of the bobbin-thread increases. This is owing to the fact that the hole through which the thread issues approaches the needle so that the thread draws with decreasing leverage on the case. The increase of tension thus given to the bobbin-thread causes a strong and firm interlocking of the two threads.

By means of my improvements I provide a loop-check which never fails to detain the loop, and never subjects the same to excessive strain. I give the bobbin-thread a uniform tension, notwithstanding the increasing resistance of the bobbin. I increase the tension of the bobbin-thread momentarily at the completion of each stitch. I provide means by which the tension may be made extremely light or heavy at will, and by which the under thread may be held straight on the face of the fabric for button-holes; and, lastly, I enable the needle-thread to pass over the bobbin and case with great ease, so that there is no danger of either thread tearing loose in light fabrics, or of the needle-thread being detained and caught a second time by the rotating hook.

Having thus described my invention, what I claim is—

1. The bobbin-case *D*, provided with the hook or check *r*, arranged to operate substantially as described.
2. The bobbin-case *D*, provided with the recess *s*, to facilitate the passage of the thread, as shown and described.
3. The bobbin-case *D*, provided with the spring *k*, having the lip *n* projecting through the case, substantially as shown and described.
4. The rotating hook *B*, having its recess to receive the bobbin, arranged eccentrically substantially as and for the purpose described.
5. In a sewing-machine, a bobbin-case which is turned backward by the bobbin-thread while said case is held under the pressure of the needle-thread, substantially as herein described.
6. The bobbin-case *D*, provided with the recess *s*, and with the hole or holes *j* in its upper side, as shown and described, and for the purpose set forth.

OSCAR FARRAR.
